F. HEITZLER

METHOD OF IDENTIFYING PRECIOUS STONES

Filed April 28, 1927

UNITED STATES PATENT OFFICE.

FRANK HEITZLER, OF BOSTON, MASSACHUSETTS.

METHOD OF IDENTIFYING PRECIOUS STONES.

Application filed April 28, 1927. Serial No. 187,211.

This invention pertains to a method of identifying precious stones, particularly those of a transparent nature. One of the greatest difficulties incident to the recovery of 5 precious stones which have been lost or stolen is positive identification of such stones. This is due first to the fact that aside from weight and style of cut, which of course are characteristics common to many stones of a given 10 kind, the only identifying features usually available are color, and water or brilliancy. Since there is seldom any fixed standard of color available with which a given stone may be compared to facilitate identification and 15 since the brilliancy of a stone is a purely relative term, it is often very difficult, if not impossible, to make any positive identification of the stone which is suspected of having been stolen.

20 It has long been recognized that most precious stones of natural origin have certain distinct characteristics when examined microscopically, for example, imperfections or abnormal peculiarities in cutting but more particularly interruptions of their optical homogeneity, all of such distinct peculiarities being hereinafter referred to for convenience as "defects". These defects may consist, for 25 example, of irregularities in cutting, as above noted, but more especially such interruptions of their optical homogeneity as incipient fractures and imperfections in crystallization; included bubbles of air or gases; specks or flakes of metallic oxides, or other opaque 30 matter; and in the case of diamonds, small particles of uncrystallized carbon which appear as black spots. It is very rare indeed that a stone, particularly a diamond, is found which does not have one or more of these 35 defects, and it is most unusual to find a stone of any size which does not contain several such defects, often of different kinds. Of course, if these defects are of great size, they may detract from the value of the stone, but 40 the stone is usually so cut as to avoid so far as possible the large defects, and the remaining smaller defects, which are not usually visible to the eye or even to a low power microscope, do not seriously or even appreciably 45 detract from the appearance of the stone. Thus while for convenience I employ the word "defect" in describing these 50 peculiarities of the stone, it is with the understanding that the optical peculiarities thus referred to need not necessarily be of a char- acter such as to decrease the value of the stone.

As the inclusion of these defects is entirely fortuitous, it is substantially impossible or at least highly improbable that any two stones 60 will be found containing the same defects in the same relative positions, and thus were it possible to make note of the defects in a given stone and to keep a record of such defects, a very definite and accurate means of identi- 65 fication would be available.

As a usual thing precious stones employed for jewelry are quite small (a diamond of one-quarter inch diameter being quite unusually large and most of them being much smaller 70 than this) while the defects which must be relied upon for identification are of microscopic size and only visible through a microscope of high power. Furthermore, the mere observation of these defects is not sufficient 75 since it affords no standard of comparison by means of which the stone may be identified at a later time.

In accordance with my present method I prepare a photo-micrograph, preferably 80 using a magnification of the order of 250 diameters, although I do not wish to restrict myself to this particular magnification, it being possible that good results may be secured with either a higher or lower power. 85 In order to obtain desirable results and to produce a photographic print which will be of any value for later comparison for identi- 90 fication purposes, I find it desirable to light the stone in such a manner and to employ lenses of such character as to reduce as far as possible contrasting effects in the negative and print, this procedure being quite contrary to the usual practice in making photo-micro- 95 graphs. After such a photo-micrograph has been made and microscopically compared to the stone for its accuracy, such photo-micro- 100 graph may be filed away in any suitable custody, for example, by the seller of the stone, by the purchaser or, by the insurance company. I further contemplate that this process may be applied upon the entry of the stone into this country and that the photo- 105 micrographic record thus made may be kept at the customs house and that a duplicate may be furnished to each successive purchaser of the stone. Thus if at any subsequent time the stone should be stolen or lost such print or 110 prints would furnish an accurate and undeni- able standard of comparison with which a

stone might be compared for identification purposes.

In making such comparison it would simply be necessary to take the photo-micrograph, supposed to correspond to the suspected stone, and to examine the stone under microscopic power sufficient to exhibit defects clearly. Preferably the photo-micrographs should in each case bear a legend showing the amount of magnification employed in making it, together with other data, for example, the distances of the various defects from a fixed datum point of the stone, and in addition the print may bear other data as is often furnished to the purchaser of a precious stone, for example, a statement of the weight, style of cutting, color, etc.

While the above system of identification thus briefly outlined appears quite simple (although I believe it to be novel), I have found through a long course of experiments that the production of satisfactory photo-micrographs of precious stones, and particularly diamonds, is not at all easy if such photo-micrographs are to form reliable standards of comparison, as above described. In the first place the irregular surface presented by the facets of the cut stone, and in the case of a diamond particularly the fact of its double refractive properties, makes it exceedingly difficult to produce a photo-micrograph clearly disclosing the depths of the stone throughout its entire area. In the second place the defects which occur in such a stone do not necessarily lie in a single plane parallel to the plane of the photograph but in fact usually occur in planes spaced from one another throughout the depth of the stone.

Lenses used for photo-micrography are necessarily of such character that the depth of focus is exceedingly short in order to obtain the desired clearness of definition, it being a well known principle of optics that any attempt at increase in depth of focus necessarily results in reducing definition. Thus in order to focus sharply upon a defect which occurs, for example, near the top or front face of the stone, the lens will not produce a sharp image (and often forms no image at all) of defects lying but a short distance, for example one half of a millimeter, below or behind the plane of the selected defect. Thus if, for example, a large stone having a defect near its front surface were photographed for identification purposes and the lens were so focused as to show this defect at the front of the stone, it would fail to show other defects, so that this single defect would ordinarily constitute the only means of identification. While this might be of some utility, it is not all that could be desired since there is at least a very remote possibility that two stones might be found having a single defect of substantially the same shape and kind and in the

same location. It is thus desirable in order that the process may be of real commercial value that the photo-micrograph show substantially all or at least several of the defects in the stone. Accordingly my preferred method consists in making such photo-micrographs in which defects occurring at different planes of the stone are shown upon the same print and with substantially the same sharpness of definition.

To accomplish this result I prefer to employ apparatus such as is more fully disclosed in my copending application Serial No. 187,212 filed April 28, 1927. By means of this apparatus I first examine the stone microscopically to determine defects lying for example at or near the front or top surface of the stone. I then vary the relative position of the stone and lens so as to focus upon a plane of the stone which is deeper within the latter and then again examine the stone for defects at this plane. I may thus continue with a series of settings of the lens until I have determined with accuracy those planes in which substantial defects are to be found, noting and recording the position of each such plane. I then expose a photographic plate to a magnified image of the stone, such image being that of the first plane in which a defect was found. After exposing the plate to this image I readjust the camera lens so as to impose upon the plate the image of the next plane in which I have previously found by exact measurement that defects occur. I expose the same plate again to this image, and may if necessary, continue, by repeated exposures upon the same plate, to register images of all of those planes of the stone in which substantial defects occur.

Upon development of this exposed photographic plate I find that it shows substantially all of the defects occurring throughout the depth of the stone, clearly and with sharp definition and in their proper relative positions. This negative may be used to make suitable prints, and since as above described it is seldom that the stone does not exhibit more than one defect, such a print, showing all of the defects in one view, is exceedingly valuable as a means of identification of the stone since the various defects occurring in the stone are usually of distinctive shape and are at definite distances from some fixed datum point, for example, the front surface of the stone. Oftentimes the defects, for example, cracks or flaws, are of curious and grotesque outline while the spots or specks of carbon usually occur in flocks or groups in which the relative arrangement of individual particles is quite distinct.

As a variant of the above method I may make successive exposures upon different plates and after developing superpose the several negatives and print through them all at

the same time, but except in unusual cases I prefer the first procedure as more simple and accurate.

While my method may undoubtedly be carried into effect in various ways it is essential from the commercial standpoint that it be capable of use by relatively unskilled persons and that it be possible to prepare composite photo-micrographs quickly at relatively low cost. With these objects in view I have designed the apparatus shown in the accompanying drawings, such apparatus being highly effective for the purpose and wholly practical from the commercial standpoint, although I wish it to be understood that the apparatus disclosed is merely illustrative of various devices which undoubtedly may be employed for carrying the process into effect.

In the accompanying drawings Fig. 1 is a plan view of suitable apparatus for use in practicing the method herein disclosed;

Fig. 2 is a side elevation partly in section of the same apparatus;

Fig. 3 is a rear elevation of a device for holding unmounted stones in proper relation to the axis of the photographic lenses;

Fig. 4 is a section, to larger scale, on the line 4—4 of Fig. 3, showing an unmounted stone held in position for photography;

Fig. 5 is a front elevation illustrating the focusing screen or ground glass of the camera as provided with centering graduations;

Fig. 6 is a diagrammatic side elevation of an unmounted stone showing defects at different distances from its front face;

Fig. 7 is a view, to larger scale, illustrating the appearance of the magnified image of a stone upon the focusing screen of the camera showing defects occurring, for example, in the plane 8—8 of Fig. 6; and

Fig. 8 is a view showing the general appearance of a photo-micrographic print made in accordance with the present method and showing defects in the planes 8—8 and 9—9 of the stone of Fig. 6, together with a suitable descriptive legend.

While my novel method may doubtless be carried out by the use of other means than that herein disclosed, I have found the apparatus illustrated in the accompanying drawings to be very satisfactory for the purpose and to give excellent results. This apparatus comprises an elongate base or bed 1 which may be made of wood, metal or other suitable material and which supports the camera, the means for holding and lighting the stone, and other accessories described hereinafter more fully. Preferably the camera is mounted upon one end of this base or bed 1 and comprises the backboard 2 connected by the bellows 3 to the front or lens board 4. The front board 4 is mounted upon a support sliding on or in suitable guides extending longitudinally of the base 1 and this

support is furnished with one or more racks 5 engaging a pinion or pinions 6 carried by a transverse shaft 7 mounted in bearings in the bed 1. This shaft projects laterally beyond the bed and is connected to suitable reduction gearing, not shown, contained within the box or casing 8. This reduction gearing may comprise worm wheels and gears or such other mechanism as is usual for producing a very slow movement of a driven part. An actuating shaft 9 extends into the casing 8 and is connected to the reduction gearing, such shaft 9 preferably extending to a point adjacent to the backboard 2 of the camera and being furnished with a knurled knob or disk 10 by means of which the shaft may be turned. By turning this shaft the front or lens board of the camera may be moved very slowly and with great accuracy.

The front board 4 is preferably provided with a laterally extending bracket arm 11 which normally engages a sliding actuator bar 12 of a micrometer indicator 13. This micrometer indicator may be of any usual type, preferably reading to one hundredths of a millimeter, and is furnished with an index needle 14 cooperating with a scale 15. Preferably the scale is carried by a movable ring so that the zero point of the scale may be adjusted. This type of micrometer indicator is old and well known and in itself forms no part of the present invention. Preferably this indicator is bodily adjustable longitudinally of the bed 1 but is normally fixed in position. As one convenient means of mounting the indicator, I fix a rod 17 by means of brackets 18 to the edge of the bed 1, the rod being spaced from the bed, and by means of any suitable clamp (not shown) secure the indicator to the rod.

The lamp 19 is mounted on a standard 20, preferably adjustably secured to the bed 1 and the lamp may be provided with reflectors and with condensing lenses in a telescopic casing 21 so as to throw a parallel beam of light along the axis of the camera lens.

The holder for the stone to be photographed preferably comprises a base plate 22 adjustable longitudinally of the bed and which may be secured in adjusted position by means of the set screw 1^a. This plate 22 carries a second plate 22^a having a transverse slot 22^b for the reception of a locking screw 22^c. The plate 22^a is thus adjustable transversely of the bed 1 with respect to the plate 22. The plate 22^a carries a substantially vertical standard comprising the lower portion 23 and the upper portion 24, said upper and lower portions being united by a hinge 25 permitting the upper portion, when desired, to be swung downward into a substantially horizontal position. In order to hold the upper part 24 of the standard in vertical alignment with the lower portion, I provide a pair of spaced ears or brackets 26 project-

ing from the part 24 and a lower ear of bracket 26^a projecting from the part 23, the bracket 26^a normally fitting between the brackets 26. The several brackets are furnished with aligned openings for the reception of a locking pin 27 which normally extends through the openings and thus holds the parts 23 and 24 in rigidly aligned position.

10 The upper part 24 of the standard comprises a disk-like portion 28 of annular form and this disk is provided with a rim-like flange 29 forming a retainer for a cam disk 30 which is disposed against the rear face of 15 the disk 28. This cam disk 30 is free to rotate relatively to the disk 28 and I provide a handle 31 for turning the cam disk.

10 The cam disk 30 is furnished with a plurality of cam slots 32, four such slots being shown herein. Each of the cam slots 32, receives a rearwardly directed pin 33 carried by a corresponding holder bar 34. These bars 34 are preferably disposed radially with respect to the center of the 25 disk 28 and slide in suitable guideways in or carried by the disk 28. Preferably these holders 34 are urged inwardly by means of springs (not shown) and their inner ends project into the central opening or 30 aperture 35 in the disk 28. By actuation of the handle 31, the cam disk 30 is rotated and by means of the cam slots 32, acting upon the pins 33, the several holder bars 34 are simultaneously retracted, thus leaving a space 35 between their inner ends for the reception of a stone 36. The inner ends of the bars 30 are of substantial thickness so as to provide broad surfaces for engagement with the edges of the stone, thus preventing the 40 stone from tilting or tipping after the several bars have been brought into contact with it.

10 In order to facilitate the location of the stone between the ends of the holder bars 45 and to make certain that the front face of the stone lies perpendicular to the axis of the lens, I provide a cover plate 38 (Fig. 4) having a handle 39, said plate being adapted to engage the front face of the disk 28. To 50 hold this cover plate temporarily in position I provide a pair of pins 37 projecting forwardly from the disk 28, such pins preferably having enlarged heads adapted to overlie the forward surface of the cover plate 55 38. The pins 37 are spaced apart a distance slightly less than the diameter of the cover plate 38 so that it is possible to push said cover plate edgewise between the pins until it jams and is thus frictionally held.

10 The backboard 2 of the camera carries the 60 focusing screen 42 (Fig. 5) which may be of ground glass as is usual, but I preferably provide this screen with a graduated scale or scales 43 in which the graduations preferably extend in opposite directions from a

zero point at the center, such zero point lying upon the optical axis of the lens.

10 If desired I may interpose a diaphragm 85 either between the lamp 19 and the holder for the stone, or between the holder and the 70 camera lens, such diaphragm being provided with an aperture which may be adjustable or not, as desired. Since such diaphragms are well known in the optical arts, it is unnecessary to describe this diaphragm in detail 75 herein except to say that it may be mounted upon a standard 87 which, as more fully disclosed in my copending application Serial No. 187,212 filed April 28, 1927, may be fitted into a suitable socket carried by the stone 80 supporting standard, or which may have an individual foot adapted to be secured to the bed 1.

10 The operation of the above apparatus is substantially as follows, it being assumed 85 that an unmounted stone is to be examined and photographed. The operator first applies the cover plate 38 to the forward face of the stone supporting standard, temporarily retaining the cover plate in position by 90 engagement with the pins 37. He then removes the locking pin 27 and swings the upper part of the standard down to a substantially horizontal position. The handle 31 is now moved to retract the sliding holders 95 34 and the stone to be photographed is dropped into the space between the inner ends of the holders so that the table surface 41 of the stone rests upon the exposed upper surface 41 of the cover plate 38. The handle 100 31 is now released, permitting the holders 34 to move inwardly until their inner ends engage the stone, thereby gripping and properly centering the latter. The upper part of the standard is now swung back to its normal position and locked by means of the pin 27 and the cover plate 38 is then grasped by 105 means of its handle 39 and removed from between the pins 37, thus exposing the stone in properly centered position with its axis 110 substantially in the axis of the photographic lens.

10 The lamp is now lighted so as to throw a beam forwardly through the stone, lighting the entire substance of the latter. The 115 light, as above described, is controlled by means of suitable lenses and diaphragms so that it lights the stone uniformly but does not pass substantially beyond the lateral edges of the stone.

10 The operator now roughly adjusts the front board and lens 19 of his camera until he obtains an image of the stone upon the ground glass and then further carefully adjusts the lens by means of the fine racking 125 mechanism 7, 8, 9 above described until a greatly magnified image of the front face of the stone is brought into sharp definition upon the ground glass. By adjusting the standard 23 laterally the center of the image 130

is brought to the zero mark on the focusing screen scale and the diameter of the image is now preferably noted with reference to the scale and recorded. The operator now 5 takes a magnifying glass of high power and examines the enlarged image of the stone on the ground glass, searching for any defects which may lie closely adjacent to or upon the front face of the stone. If no 10 such defects are found in this front plane he moves the camera lens slightly so as to focus upon a plane, for example, a plane one half of a millimeter within the depth of the stone. He again examines the stone at this 15 plane for defects and, assuming that he discovers a defect in this plane, he makes note of this fact and preferably sets the micrometer gage above described so that it indicates zero, the contact member 12 of the gage being then in engagement with the arm 11. He 20 also notes the diameter of the image by reference to the scale on the ground glass and also notes and records the lateral position of the defect or defects as indicated by the scale, 25 making a record of these observations.

The operator now again adjusts the camera lens to focus upon a plane still deeper in the stone, and if he discover defects in this plane, he notes the reading of the micrometer gage 30 which thus gives him the depth of this second plane behind the first plane in which defects were discovered. He thus continues examining each plane of the stone in which distinctive defects occur and recording by reference to his micrometer the location of each 35 such plane.

Having examined the entire stone in this manner he then racks the lens back substantially to its original position, inserts a loaded 40 plate holder and moves the lens by reference to the micrometer gage until it occupies that position in which an image of the first plane having a defect therein is formed upon the ground glass (i. e., the zero micrometer position) as determined by his original inspection. He now exposes this plate for the proper interval and then, after closing the camera shutter, he again moves the lens until the micrometer gage shows a reading corresponding to the second plane in which 45 defects were found. The shutter is now opened and the second exposure made upon the same plate, this second exposure imprinting upon the same plate an image of the second plane 50 in which defects occur, such image being accurately registered with the first image. Usually two exposures are enough for practical purposes but the operator may continue to make exposures upon this plate (within 55 the limits of its capacity) corresponding to each plane in which he has previously noted defects, setting the camera before each exposure by means of the micrometer gage and with reference to his previous readings.

When enough of the characteristic defects

has been photographed to insure proper identification of the stone, the plate is removed, developed and fixed in the usual way and employed in making prints. These prints as above described show the various defects 70

existing in the stone in their relative lateral positions and in their proper and peculiar shapes and groupings. For example, if the first plane of the stone in which a defect is found to occur is the plane 8-8 of Fig. 75 7, the first image which is photographed may have the appearance of that shown in Fig. 8 wherein the defects D¹, consisting of groups of minute carbon specks, are clearly and definitely shown and their relative lateral positions and distances from the center of the image may readily be noted. Considering now that the stone shown in Fig. 7 contains further defects D² in the plane 9-9 and that the second exposure of the plate is to the enlarged image of this plane of the stone, the photographic print, when finally developed, will have the appearance shown in Fig. 9 80 wherein not only the defects D¹ found in the plane 8-8 are shown but also the defects D² 85 occurring in the plane 9-9. This print also is preferably provided with certain data for use in subsequent comparison, such data comprising, for example, a statement of the magnification employed in making the negative, the depth of the planes 8-8 and 9-9 behind the front face 41 of the stone, the diameter of the image upon the ground glass and the distances of the defects D¹ and D² from the axis 90 of the image.

If at any later time it be necessary to identify the stone it is merely sufficient to mount the stone in an apparatus of the general type above described and to compare its image upon the camera screen with the image shown 100 in the photograph. As the photograph bears a legend, as above described, stating the several planes in which defects occur, it is very easy to make comparison by focusing on each of these several planes in turn and looking for 105 the defects which the photograph shows to occur in each of these planes. While the apparatus hereinabove described is convenient for this purpose it is not wholly necessary for examining the stones for identification 110 purposes since a microscope of usual type might be employed or alternatively the image of the stone might be thrown upon a large screen by means of stereopticon apparatus, or in fact any suitable means may be employed for producing the enlarged image. However, I find it advantageous to provide a 115 portable viewing apparatus (not herein illustrated) which comprises an adjustable lens and a ground glass screen mounted in the opposite ends of an adjustable holder consisting, for example, of a pair of telescoping tubes. For convenience such tubes may be relatively adjustable by means of a micrometer adjustment provided with a scale to indi- 120 125 130

cate the relative movement of the screen and lens in examining different planes of the stone. As this apparatus forms no part of the present invention and is not claimed herein, further description is unnecessary.

If instead of an unmounted stone it be desired to examine a mounted stone, for example one held in a ring, an appropriately modified form of holder may be substituted for that hereinabove described. In making photo-micrographs of mounted stones, it may be necessary to employ incident light, that is to say, light directed laterally or vertically upon the forward or side face of the stone, and while this arrangement of lighting may be necessary in certain cases, I prefer if possible to employ the lighting above more specifically described.

While I have described a certain series of steps in performing my method, together with desirable apparatus for use in the practice of the same, I wish it to be understood that the method is not necessarily confined to this particular order of steps or to the whole number of steps described, or to the apparatus herein illustrated, but that other and equivalent steps may be substituted for those hereinabove described and that in some instances certain of the steps described may be omitted without departing from the spirit of the invention.

I claim:

1. That method of identifying transparent precious stones which comprises as steps projecting upon a screen a magnified image of that plane of the stone in which a defect occurs, measuring and recording the distance of the defect from a definite datum point of the image together with distinctive characteristics of the defect, and employing said record for subsequent identification of the stone.

2. That method of identifying transparent precious stones which comprises as steps projecting upon a screen a magnified image of one plane of the stone in which a defect occurs, measuring and making a permanent record of the diameter of the image and the distance of the defect from a fixed datum point of the image, measuring and making a permanent record of the depth of the defect from the front face of the stone, and employing the records thus obtained for subsequent identification of the stone.

3. That method of identifying transparent precious stones which comprises as steps producing a magnified image of the stone at a plane in which a distinctive defect appears, recording identifying characteristics of said defect, producing a magnified image of the stone at another plane in which a distinctive defect appears, recording identifying characteristics of said second defect, recording the distance between said planes, and employing the record thus obtained for subsequent identification of the stone.

4. That method of identifying transparent precious stones which comprises as steps projecting upon a screen a magnified image of a plane of a stone in which a defect occurs, measuring and making a permanent record of the diameter of the image and the distance of the defect from a selected definite point of the image, projecting upon the screen a magnified image of a second plane of the stone in which a defect occurs, measuring and making a permanent record of the diameter of said second image and the distance of the defect from a selected definite point of the image, and employing said records for subsequent identification of the stone.

5. That method of identifying transparent precious stones which comprises as steps focusing a camera lens upon a plane of the stone in which a defect occurs, accurately measuring the distance between said defect and a fixed datum point of the stone, making a photo-micrographic print showing such defect, and employing such print for subsequent comparison in identifying the stone.

6. That method of identifying transparent precious stones which comprises examining the stone microscopically to discover defects therein, accurately determining the plane, with reference to a fixed datum point of the stone, at which such a defect occurs, making record of the distance between said plane and datum point, preparing a photo-micrograph showing the defects at said plane, and employing such photo-micrograph for subsequent comparison in identifying the stone.

7. That method of identifying transparent precious stones which comprises making a photo-micrographic record of a plurality of distinctive defects in a stone, measuring and recording the distance between said defects and a fixed datum point of the stone, and employing said record for subsequent identification of the stone.

8. That method of identifying transparent precious stones having internal defects therein which comprises as steps accurately measuring and making record of the relative locations of at least two defects within the substance of the stone, photographically recording the appearance of said defects, and employing the records in subsequent identification of the stone.

9. That method of identifying transparent precious stones which comprises as steps microscopically examining the stone in a plurality of parallel planes, carefully measuring the distance of each plane in which distinctive defects occur from a fixed datum point of the stone, making record of such measurements, photo-micrographically recording the defects in at least two of said planes, and employing such photo-micrographic record for subsequent identification of the stone.

10. That method of identifying transparent precious stones which comprises as steps

measuring by micrometer measurement the distance between two planes of the stone in each of which a defect occurs, making a record of this distance and a photo-micrograph of each of said defects, and employing this record and the photo-micrographic representations of the defects for subsequent identification of the stone.

11. That method of identifying transparent precious stones which comprises as steps making a photo-micrographic record of a plurality of defects in the stone together with a record of the distance, along an optical axis of the stone, between the planes in which such defects occur, and employing such record for subsequent identification of the stone.

12. That method of identifying transparent precious stones which comprises as steps mounting the stone before a photo-micrographic camera lens, adjusting the lens by the use of a focusing screen until the screen shows an image of the stone in which defects appear sharply defined, making permanent record of the exact setting of the lens, making a photo-micrograph of the stone with this predetermined adjustment of the lens, and employing this photo-micrograph and record of the lens setting for subsequent comparison in identifying the stone.

13. That method of identifying transparent precious stones which comprises as steps exposing the stone before a photo-micrographic camera lens, adjusting the lens by the use of a focusing screen until a sharply defined image of the front face of the stone appears upon the screen, accurately determining and recording the position of the lens, again adjusting the lens until the screen shows an image of a plane of the stone in which a defect occurs, accurately determining and recording the position of the lens at this point, making a photo-micrograph of the stone with the lens in its latter position of adjustment, and employing the photo-micrograph and the recorded measurements thus obtained for subsequent comparison in identifying the stone.

14. That method of identifying transparent precious stones which comprises as steps successively recording upon the same photo-

graphic plate magnified images of at least two planes of a stone in which defects occur, developing and fixing the plate to provide a permanent record of such defects, and subsequently forming magnified images of the stone and comparing such images with the photographic record, for identification purposes.

15. That method of identifying transparent precious stones which comprises as steps determining the relative location of a plurality of parallel planes of the stone in each of which a defect occurs, successively exposing a photographic plate to a magnified image of each of said predetermined planes of the stone, developing and fixing the plate, and employing the permanent record thus obtained for identification of the stone.

16. That method of identifying transparent precious stones which comprises as steps microscopically examining a stone and recording the distance from a fixed datum point of each of at least two parallel planes in which defects occur, exposing a photographic plate successively to the magnified images of each of said planes, developing and fixing the plate, making a photographic print from said plate, and providing the print with a legend indicative of said recorded distances.

17. That method of identifying transparent precious stones which comprises as steps successively projecting upon a screen magnified images of two planes of the stone in each of which a defect occurs, measuring and recording the distance between said planes, measuring and recording the diameter of each image and the distance of a defect from a fixed datum point of each image, photographically impressing each of said images in superposed registered relation upon the same plate, developing and fixing the plate, making a print from the plate, providing the print with a legend giving the measurements recorded, and subsequently forming magnified images of the stone and comparing such images with said print for identification purposes.

Signed by me at Boston, Massachusetts, this 25th day of April, 1927.

FRANK HEITZLER.
